7 Claims. (Cl. 309—21)

This invention relates to a novel scouring pad backing and the method of manufacturing a pad therewith. More particularly, the invention is concerned with the manufacture of cleansing or scouring devices employing metal wool filaments, such as steel wool, which may have incorporated therein soap or a like saponaceous composition.

Metal wool, for example so-called steel wool, has gained wide acceptance for household scouring of such articles as pots and pans. Scouring and polishing pads made of steel wool, which have been matted or felted together into a mass of intertwined or interwoven elongated filaments, are marketed in oval and rectangular shapes. Such household cleansing articles must be gripped by the housewife for the proper scouring or polishing effect. Unfortunately, there is a tendency for the metal wool to break or "splinter" which can result in the unpleasantness of slivers entering the skin of the user.

It would be desirable to provide a suitable backing on one side of the scouring pad so that the pad can be easily gripped and manipulated in the scouring and polishing of pots and pans. Such a grippable element would preferably comprise a sheet of paper or other sheet material having a handle formed therein and which is bonded to the metal wool pad. A paper backing sheet would be most desirable for this purpose in view of its cheapness and its ability to be printed with attractive patterns offering appeal to the user. However, in bonding such a paper backing to a metal wool pad, difficulties are encountered, particularly in high speed production.

To explain, for the steel wool article to be capable of repeated use with the backing element or handle structure, it is important that this latter element be substantially permanently bonded with respect to the body of metal wool during its period of use. To effect this bonding a considerable thickness of adhesive composition is required in order that the metal filaments of the wool will be firmly anchored in the adhesive composition and thereby locked to the backing element and to each other. However, after applying an adhesive layer of suitable thickness to a paper backing material, the backing sheet tends to curl due to the hygroscopicity of the paper. Such curling creates manufacturing problems. In the operation of placing the paper backing in place, either by mechanical means or by hand, the paper backing should be of adequate flatness for control of placement on the body of metal wool. Since the backing must usually be bonded to the metal wool body by the application of pressure as well as heat, an uncurled substantially flat paper backing avoids the non-uniform registry which could arise in attempting to flatten a curled backing into place onto the metal wool body, particularly in the case of oval, round or rectangular articles having sloping more or less uneven surfaces. Such curling may be reduced to some degree by laminating the required thickness of adhesive composition to a backing material rather than extrusion coating it. But such lamination is relatively expensive and does not assure complete freedom from a curling problem.

A need exists, therefor, for uniformly backed metal wool bodies such as scouring pads which are relatively simple and inexpensive to manufacture and which are

2

characterized by a substantially permanent anchoring of the metal wool filaments to the backing.

A method meeting the foregoing need forms the subject matter of the present invention. The article or pad made by said method comprises a body of matted interwoven elongated metal wool filaments and a backing combined with an initially free plastic film or ply of high tensile strength and dimensional stability at temperatures below 140° F.; the word "free" describes a film which is substantially unbonded or not adhered to the backing prior to activation through heat or otherwise and hence does not contribute to curling; prior to activation the film is, however, located intermediate the backing and the surface of the metal wool body to be contacted, such location preferably being effected by mounting the free film at one or more spaced points on the backing as hereinafter described. The free film preferably has a thickness substantially equal to or greater than the largest cross-sectional dimension of the metal filaments and when activated is capable of receiving filament loops therein to the extent that a substantial plurality of loops of each of said filaments may have the composition of the film fused around adjoining filament loops. Thus, the film of plastic is of such thickness that when the plastic is activated it will melt and flow around the filaments. As a result the film and filaments are integrally interlocked to the extent that such interlocked filaments will be unwoven from the metal wool body should the backing film be pulled away therefrom and will in large measure remain anchored to the backing. The character of anchoring can be described as one wherein a substantial plurality of the filaments at the surface of the body of matted metal wool penetrate the plastic film, emerge therefrom and reenter the film, thus locking the successive loops of the filaments whereby the body of interwoven matted metal wool retains its aggregated form or shape. To effect this structure the plastic of which the film is composed should be of high tensile strength as well as dimensional stability at least at temperatures below 140° F.; that is, at those temperatures normally encountered in the household. At such household temperatures the plastic film should also remain relatively inert to the action of alkalis, hot water and soaps and should be non-toxic, odorless and of such flexibility that, at the thickness required for proper interlocking of filament loops, the film alone or in combination with a backing sheet of paper, foil, woven fabrics or the like will be flexible in use.

The mass of metal wool is preferably composed of elongated filaments of steel, which filaments are intertwined or interwoven more or less randomly with respect to one another. The metal wool preferably also has incorporated therein some form of soap or saponaceous composition which serves as a lubricant as well as a detergent effecting appropriate scouring and polishing of pots and pans and similar articles. In accord with present commercial practices, the metal wool mass can be assembled into a suitable pad having an oval or rectangular outline and can be of a compressible, springy nature such that it will yield upon the application of pressure when the backing film is being interlocked with respect to the metal wool filaments. The surface of the pad will preferably be flat on that side of the pad which is to receive the backing film but may be rounded or sloping, particularly near the marginal edges of the pad.

The film may be of any suitable activatable plastic which lends itself to liquefaction through the action of heat or a solvent serving to melt the plastic so that it will receive the filament loops within the plastic film and then solidify to insure interlocking. Although well-known adhesive resins can be activated by use of such solvents

as hot acetone and methyl ethyl ketone, such adhesive resins and the solvents therefor are less preferred since their use introduces problems of solvent recovery and safety control. It is preferred to employ the heat activated adhesives whereby heat may be applied to the free film, preferably through the backing; upon melting the composition forming the free film it will rapidly transfer its heat to the metal filaments, effecting a drop in temperature of the plastic after it is momentarily liquefied and migrated around successive loops of the substantial plurality of interwoven metal filaments. Such compositions as the polymerized olefins, e.g., polyethylene, are preferably employed. Other suitable film compositions include, for example, microcrystalline waxes with added polyethylene, polyisobutylene with added paraffin; vinyl acetate; polyamides, butyl rubber emulsions; and like moisture proof adhesive resins.

The film is preferably integrated with sheet material having properties usually found in fibrous cellulosic material or paper, i.e., flexibility and tendency to absorb quantities of plastic resins applied thereto. Although paper in the common or usual sense means a material made from such sources as wood, rag, or bagasse (sugar cane), a broader interpretation of the term paper is intended herein, the term being understood to include such kindred materials as artificial and natural textile fibers which are matted and woven. Also included in the term paper are composite structures made by laminating such paper or paper-like compositions to other sheets such as plastic films, metal foil and the like which may be relied upon to offer an attractive appearance either through an applied design or the appearance of the material itself. As a rule, the paper backing sheet for use in combination with the backing film will be one capable of being printed and will range in weight from 8-90 lbs., preferably about 45 lbs. (basis 24 x 36—500=3,000 sq. ft.); various kinds of paper that can be used are: papers made from chemical pulps including sulphate papers, sulphite paper, sulphate-sulphite combination papers, soda pulp papers, these various papers being either uncoated or coated on one or both sides with a coating comprising clay, titanium dioxide, and binder; papers made from chemical pulp or chemical pulp and groundwood combinations, coated or uncoated, which have been calendered or supercalendered such as publishing papers, glassine, supercalendered sulphite papers, machine finish sulphite-sulphite papers, and machine finish and machine glazed sulphite-sulphite papers, and other materials such as cellulosic films including cellophane and cellulose acetate, foil and the like. Preferably the paper backing is embossed so as to provide a roughened surface which will facilitate gripping of the paper-backed article. The paper backing also has an outline substantially coextensive with the free plastic film and the mass of metal wool, and as indicated, this outline may be oval, rectangular, round, or some other suitable shape.

In accordance with a preferred practice of this invention an uncoated sheet of paper is laminated to a body of matted metal wool filaments through the intermediation of an interposed ply of heat activatable thermoplastic adhesive. In the resulting structure, such ply, upon liquefaction and migration, combines with the paper to form the backing for the structure. Preferably, the interposed ply of plastic is suitably anchored on part of its surface to the backing paper, as will be explained in detail hereinafter, to insure proper registry of the backing paper to the body of metal wool and the interposed ply. When the paper backing sheet, the metal wool filaments and said ply are in position opposite one another, pressure and heat are employed to activate the plastic ply in order that successive loops of each of a plurality of metal filaments will have fused plastic therearound. The resulting structure, throughout its formation, is characterized by uniformity of placement of the backing due to the freedom from curling of the backing sheet. Further-

more, for a given weight of plastic, an improved bond is obtained with the metal filaments.

In a second form of the invention a very thin precoated sheet of paper is laminated to a body of matted metal wool filaments through the intermediation of an interposed free ply of heat activatable thermoplastic adhesive.

The preferred embodiment of the invention is shown in FIGS. 1 through 4, which illustrate the principle of a handle structure incorporated as part of the backing. The second embodiment is shown in FIG. 5.

FIG. 1 is a side elevation of a paper-backed scouring pad; FIG. 2 is a top plan view of the scouring pad in FIG. 1; FIG. 3 is a side elevation of the pad in FIGS. 1 and 2 taken in section along line 3—3 in FIG. 2; FIG. 4 is an enlarged sectional view showing the relationship of the paper backing and the free plastic ply mounted thereon; FIG. 5 is a partial view, similar to FIG. 4, but showing a modification.

As seen in FIGS. 1-4, the free plastic ply 10 is mounted on the backing paper 12 so as to insure complete registry of said ply between the paper backing and the metal wool 13 when the elements are brought face-to-face and bonded. Such mounting may be effected by "spot-welding" the plastic ply at spaced points on the surface of the backing sheet but, preferably, ply 10 is integrated with part of a handle 14 of the type shown in the drawings such that ply 10 serves the dual function of joining the pair of upwardly extending folded backing paper portions 16 and 18 which are juxtaposed and adhered together through the intermediation of the adjoining and folded portions 20 and 22 of the ply 10. However, the present invention is not to be restricted to such details, although they are preferred, and instead any suitable means for mounting the free plastic ply 10 with respect to the paper backing 12 can be employed, in all of which instances plastic ply 10 is unbonded with respect to paper backing 12 and metal wool mass 13 on a majority of its surface.

Flap portions 30 and 32 of the paper backing 12 do not curl, and so meet evenly with flap portions 34 and 36 of plastic ply 10. To receive flap portions 34 and 36 evenly, the matted metal wool pad 13 is flattened on its upper face 15 in order to assure complete anchorage of the ply 10 along the faces of flap portions 34 and 36.

In production, a plurality of the composite backings of FIG. 4 in a magazine with suitable feed means is serially introduced onto a succession of matted metal wool pads, means being employed to positively pass each of the metal wool pads at a uniform rate past the magazine feed and assure proper registry of the plastic ply with the flattened upper face of the pad. Immediately after such placement the backing and the pad are constrained to pass between travelling endless belts, rotating rollers or other suitable pressure applying means engaging the backing and the pad respectively for delivery past an activating station. In one form, this station may comprise heating means in the form of an electric resistance element or the like contacting the backing either directly or transferring heat thereto indirectly through the means used to maintain the backing and the pad under pressure. The heat transferred to the backing should be below that temperature whereat the paper backing 12 will burn or char but should produce a sufficiently elevated temperature to activate the intermediate ply 10 so that it melts, pressure being maintained for a sufficient period of time during the molten state of such plastic to assure that a plurality of the metal wool filaments on the upper face 15 of the pad are immersed in the molten plastic so that successive loops of such filaments are interlocked by being at least partially surrounded by the plastic of intermediate ply 10. As indicated, heat may be applied to either or both sides of the backing-pad combination, but it has been found preferable to apply heat through the backing only whereby the relatively cool filaments of metal wool pad will more rapidly permit transfer of heat thereto.

from the molten plastic plies to effect rapid solidification. To assist in resolidification of the thermoplastic, cooling means may be employed after suitable bond has been effected between the filament loops and the backing, which cooling means are employed while the backing and the metal wool pad are maintained under pressure.

It has been found that the plastic material of ply 10, when rendered molten, tends to flow onto the metal filaments in a satisfactory manner and to interlock well with the filaments, producing a very firm bond.

The embodiment of FIG. 5 is like that of FIG. 4 except that a precoating 28 is present on the backing paper 12'. Thus, the FIG. 5 structure comprises the precoated paper backing 12', a substantially free floating plastic ply or film 10', and a handle 14', the latter being formed by the folded portions 16' and 18' of paper 12', by the folded portions 24 and 26 of precoating 28, and by folded portions 20' and 22' of the ply 10'. The metal wool pad may be attached to the structure of FIG. 5 substantially in the manner and by the means described above, it having been found that the ply 10' can be bonded to the paper 12' through the precoating without the incidence of curling. The thickness of the ply 10' may be up to 6 mils, more or less.

The term "precoated" refers to the operation of applying a thin coating of activatable thermoplastic adhesive composition to the paper backing material either by lamination or extrusion coating to provide a bond between the paper fibers and the intermediate ply of plastic or adhesive resin. In the structure eventually produced by use of a precoated paper, the composition of the precoating and the intermediate ply, upon liquefaction and migration or intermingling, form the backing film of the structure. Preferably, as in the case of FIGS. 1-4, the interposed ply of plastic is suitably anchored on part of its surface to the precoated backing paper to insure proper registry of the backing paper to the body of metal wool and the plastic ply. When the paper backing sheet, the metal wool filaments and the intermediate ply of thermoplastic adhesive composition are in position opposite one another, pressure and heat are employed to activate the composition of the precoating and the plastic ply in order that successive loops of each of a plurality of metal filaments will have fused plastic therearound.

The material used to "precoat" the paper backing sheet may be any suitable heat activatable thermoplastic composition and preferably will be of the same composition as the intermediate free ply used to adhere the precoated paper backing to the mass of matted metal wool. Such compositions as those listed hereinabove identifying the free film may be employed. The material used to precoat the paper backing will generally be applied in a thickness less than that of the intermediate ply of plastic adhesive and, as indicated, may be applied either by extrusion coating or by lamination. The precoating composition will have a thickness which does not occasion curling of the paper backing but will be sufficient to provide suitable bond between the paper fibers and the plastic ply and the metal wool. In general, it has been observed that a thickness in the range of 1 to 4 mils will offer a suitable extent of continuous bonding between the paper and the plastic ply without introducing curling difficulties, although it has been found that a thickness on the order of 2 mils is preferred.

The material of the intermediate bonding ply of thermoplastic, as indicated, is preferably of the same composition as that of the precoating. For example, polyethylene will be employed as the intermediate ply when the precoating material is composed of polyethylene. Usually, the thickness of this intermediate ply of plastic will be greater than the thickness of the coating applied to the paper and should be in excess of that required to offer suitable anchorage to the metal filaments embedded in the plastic upon its activation or conversion into a plastic flowable condition. The maximum thickness of the inter-

mediate ply of plastic will be dependent to some extent upon the flexibility of the plastic ply which is preferably bent to form part of a handle structure integral with the paper backing. Usually a thickness less than about 6 mils in the case of polyethylene will offer the satisfactory reservoir for anchorage of the metal filaments and for bonding with the activated "precoating."

By virtue of the thinness specified for the precoating 28, flat portions 30' and 32' of the paper backing 12' do not curl, and so meet evenly with flap portions 34' and 36' of plastic ply 10'.

While the present invention has been described with particular reference to specific examples, it is not to be limited thereby, but reference is to be had to the appended claims for a definition of its scope.

What is claimed is:

1. A paper backing adapted to be affixed to an element, comprising a sheet of paper, and a free film of heat activatable thermoplastic adhesive anchored on only a part of its surface to a surface of said paper sheet and having an outline when opposite said sheet substantially coextensive therewith, a portion of said film being folded into face-to-face abutting relation with an adjoining portion thereof, a portion of said sheet being folded into face-to-face abutting relation with an adjoining portion thereof through the intermediation of said folded film portions to provide a grippable handle on said backing, said film being anchored to said sheet only at said grippable handle.
2. A paper backing adapted to be affixed to an element by means of heat, comprising a precoated sheet of paper, and a ply of heat activatable thermoplastic adhesive anchored on only a part of its surface to the precoated surface of said sheet and having an outline when opposite said sheet substantially coextensive therewith, a portion of said ply being folded into face-to-face abutting relation with an adjoining portion thereof, a portion of said paper sheet being folded into face-to-face abutting relation with an adjoining portion thereof through intermediation of said folded ply portions to provide a grippable handle on said backing, said ply being anchored to said sheet only at said grippable handle.
3. A process of forming a scouring pad having a backing sheet adhered thereto, comprising providing a flexible backing sheet, providing a film of heat activatable thermoplastic adhesive having an outline when opposite said backing sheet substantially coextensive therewith, anchoring said film to said backing sheet only along parts of a surface of said backing sheet, positioning said film opposite said backing sheet, disposing a body of matted, interwoven, elongated, metal wool filaments against said film, applying heat to said film to activate said film and unite it with said body and said backing sheet, and withdrawing the heat.
4. A process of forming a scouring pad having a backing sheet adhered thereto, comprising providing a flexible backing sheet, providing a film of heat activatable thermoplastic adhesive having an outline when opposite said backing sheet substantially coextensive therewith, anchoring said film to said backing sheet only along parts of a surface of said backing sheet, positioning said film opposite said backing sheet, disposing a body of matted, interwoven, elongated, metal wool filaments against said film, simultaneously forcing said backing sheet and said body together and applying heat to said film to activate said film and unite it with said body and said backing sheet, and withdrawing the force and heat.
5. A process of forming a scouring pad having a backing sheet adhered thereto, comprising providing a flexible backing sheet, providing a film of heat activatable thermoplastic adhesive having an outline when opposite said backing sheet substantially coextensive therewith, positioning said film opposite said backing sheet, anchoring said film to said backing sheet only at central portions of said backing sheet and said film, disposing a body of

7
matted, interwoven, elongated, metal wool filaments against said film, applying heat to said film to activate said film and unite it with said body and said backing sheet, and withdrawing the heat.

6. A process of forming a scouring pad having a backing sheet adhered thereto, comprising providing a flexible backing sheet, providing a film of heat activatable thermoplastic adhesive having an outline when opposite said backing sheet substantially coextensive therewith, positioning said film opposite said backing sheet, spot-welding said film to said backing sheet only at spaced portions of a surface of said backing sheet, disposing a body of matted, interwoven, elongated, metal wool filaments against said film, applying heat to said film to activate said film and unite it with said body and said backing 10 sheet, and withdrawing the heat.

7. A paper backing adapted to be fixed to an element, comprising a sheet of paper having two opposed margins, and a free film of heat activatable thermoplastic adhesive

5
having an outline when opposite said sheet substantially coextensive therewith, said film being anchored to said sheet only at a central portion of said sheet which extends between and to said opposed margins and thereby providing areas of said film on either side of said central portion which are unattached to said sheet.
